UNITED STATES PATENT OFFICE.

LOUIS E. MORRISON, OF SALIDA, COLORADO.

VALVE FOR WATER LIFTS.

Application filed October 16, 1924. Serial No. 744,035.

This invention appertains to slide valves and more particularly to an improved valve mechanism for controlling the flow of an operating fluid for a piston and cylinder.

5 Another object of the invention is to provide a novel valve and operating mechanism, which is an advancement in the art over the construction shown in my Patent 1,481,619 issued to me January 22, 1924 for pneumatic 10 water lift, and the improved valve is adapted to be utilized on a pumping system such as shown in the mentioned patent.

A further object of the invention is to provide a novel valve body and a novel rocker 15 head connected with the valve body.

A further object of the invention is to provide novel means for operating the rocker head from the piston at each end of the piston stroke.

20 A further object of the invention is to provide novel means for holding the rocker head in an adjusted position after being operated by the piston at each end of the stroke thereof.

25 A still further object of the invention is to provide an improved device of the above character, which will be durable and efficient in use, one that will be simple and easy to manufacture and one which can be placed 30 upon the market at a small cost.

With these and other objects in view, the invention consists in the novel construction, arrangement and formation of parts, as will be hereinafter more specifically described, 35 claimed, and illustrated in the accompanying drawings, in which drawings,

Figure 1 is a vertical longitudinal section illustrating the novel rocker head and valve body and the operating means for the rocker 40 head,

Figure 2 is a transverse section taken on the line 2—2 of Figure 1,

Figure 3 is a view similar to Figure 1, showing the opposite position to which the mechanism moves.

Figure 4 is a section taken substantially upon the line 4—4 of Figure 3.

Referring to the drawings in detail, wherein similar reference characters designate corresponding parts, throughout the several views the letter A generally indicates the improved valve operating mechanism, which comprises the valve casing 10 including the spaced parallel side walls 11 and 12 and the 55 end walls 13. Top and bottom walls 14 and 15 are connected with the upper and lower

end respectively of the side and end walls. The lower wall 15 is provided with ports 16 and 17, for a purpose, which will be herein-after more fully described. The rear wall 11 60 is also provided with a pair of spaced exhaust ports 18 and 19, the purpose of which will also be hereinafter more fully described.

This valve casing 10 is arranged directly on the upper end of the operating cylinder 20 and the cylinder has reciprocately mounted therein the piston 21. The piston 21 is provided with a piston rod 22 which extends out of the cylinder head along side of the valve casing 10. The extreme upper end of the 70 piston rod 22 is provided with an inwardly extending arm 23 which overlies the upper wall 14 of the valve casing.

As clearly shown in Figure 1 of the drawing the port 16 has communicating therewith 75 a pipe 24 which communicates with the lower end of the cylinder.

A semi-circular shaped slide valve 25 is slidably mounted within the casing 10 and it is obvious that when the valve is disposed at 80 one side of the casing, as to the left, as shown in Figure 1 of the drawing that the port 17 will be uncovered which will permit the flow of the operating fluid from the valve casing into the upper end of the cylinder for operating the piston 21 in one direction. When the valve 25 is slid to the right the port 16 will be opened which will permit the flow of the operating fluid from the valve casing 10 into the pipe 24 and then into the lower end 90 of the cylinder for forcing the piston 21 upwardly. This valve 25 is provided with a semi-circular port 26 and the terminals of the arcuate port 26 are provided with right angularly disposed outlet ways 27. When 95 the port 17 is uncovered, it can be seen that the arcuate port 26 over lies the port 16 which permits the exhaust of the lower end of the cylinder to flow into the port or way 26. The way 27 communicates with the exhaust port 19 so that the exhaust air can exhaust into the atmosphere.

When the slide valve of the body 25 is moved to right so as to uncover the port 16 the arcuate port 26 communicates with the port 17 and the way 27 registers with the exhaust port 18 and the air is allowed to exhaust from the upper ends of the cylinder into the atmosphere through the said port 18.

The slide valve 25 at one side of the transverse center thereof is provided with a laterally extending pin 28 which is disposed within

a notch 29 formed in the periphery of the rocking head 30. This rocking head 30 is of a substantial quadrant shape and is pivoted at a point adjacent its angle on a suitable pivot pin 31. The notch 29 is formed in the periphery of the head adjacent to the lower edge thereof. The rocking head 30 is also provided with a notch 33 the purpose of which will be hereinafter more fully described. A pair of outstanding pins 34 and 35 are carried by one face of the head 30 and these pins are arranged in spaced relation adjacent to the upper and lower ends of the head.

A valve operating rod 36 is slidably mounted within the valve casing 10 and has its opposite ends protruding respectively through the upper and lower walls 14 and 15 of the said casing and as clearly shown in Figure 3 of the drawing, the arm 23 formed on the piston rod 22 is adapted to engage the upper end of the rod 36 toward the end of the piston down stroke. The lower end of the operating rod 36 extends into the cylinder 20 and is adapted to be operated by the piston 21 of the cylinder at the end of the piston up stroke. An operating arm 37 is rigidly secured to the operating rod 36 and this arm is provided with a reduced angularly extending finger 38 which is disposed between the pins 34 and 35 and is adapted to engage the said pins upon the actuation of the rod 36 by the piston rod and the piston.

In order to hold the rocking head in an adjusted position a telescopic plunger 40 is pivoted at its upper end as at 41 to the top wall of this valve casing 10 and the lower sliding section of the cylinder carries a head 42 for fitting in the notch 33 in the rocking head. An expansion spring 43 is coiled about the plunger and normally urges the lower end of the plunger into intimate contact with the wall of the notch in the lug at all times.

In operation of the improved device, presuming that the piston 21 is at the upper end of the cylinder and the valve 35 at the left as shown in Figure 1 of the drawing, the air or other operating medium will flow into the casing through the supply pipe 44 and then through the port 17 from the casing into the upper end of the cylinder forcing the piston to the opposite end thereof. The piston rod 22 will of course be brought down with the piston and the arm 23 thereof will engage the upper end of the operating rod 36 when the piston has almost completed its working stroke and will move the rod 36 downward in its casing. This will bring the finger 38 of the operating arm 37 into contact with the pin 34 and swing the rocking head on its pivot. The pin 28 will of course be engaged by one wall of the notch 29 formed in the head and the valve body will be slid to the right so as to uncover the port 16 and move the arcuate port 26 into registration with the port 17. The

lug 32 of the rocking head will be swung on the other side of the pivot of the rocking head and the spring pressed plunger will normally hold the head in the position just described until again operated. The compressed air from the casing will now flow through the pipe 24 to the lower end of the cylinder and thus force back the piston to its raised position and when the piston is nearing the end of its travel the upper end thereof will engage the operating rod 36 and raise the rod and move the finger 38 in engagement with the upper pin 35 of the rocking head, swinging the head on its pivot 31. The movement of the head will slide the valve body 25 to the left again uncovering the port 17. The telescopic plunger 40 will now assume the position shown in Figure 1 of the drawing and normally hold the rocker head in the position shown.

From the foregoing description, it can be seen that I have provided a novel valve operating mechanism of exceptionally simple and durable construction, which will effectively accomplish the purpose intended.

Changes as to details may be made without departing from the spirit or the scope of this invention, but:—

What I claim as new is:—

1. A valve structure of the character described, comprising a closed chest having an inlet, exhausts and a pair of outlets to an engine cylinder, an outlet, a sliding valve block acting when actuated to open or close one of said outlets and connect the other outlet with an exhaust, a pin member projecting from one face of said valve block, a quadrant body pivotally mounted within the chest and having a notch formed therein for loosely receiving said pin, a pair of spaced pin members upon one face of said body, a reciprocable arm within the chest alternately engaging the pin of said quadrant to oscillate the same upon its pivot and to cause the quadrant to impart reciprocatory movement to the valve block means controlling said quadrant for imparting a snap action to the movement thereof.

2. In combination, in a mechanism of the character described a cylinder, a reciprocable piston within said cylinder, a piston rod carried by the piston and extending from one end of said cylinder and having a laterally directed arm upon the free outer end thereof, a valve structure arranged adjacent that end of said cylinder from which said piston rod projects, comprising a chest having a main inlet, a pair of exhausts and a pair of outlets, each of said outlets leading into said cylinder at one side of the piston, a reciprocatory valve body within the chest adapted to alternately set up communication between an outlet and an exhaust and open an outlet and an exhaust, an oscillatory element within said chest operatively engaging said valve body, a rod extending through said chest and having one

end projecting into said cylinder for engagement by the piston and the other end adapted to be engaged by said lateral arm, means whereby upon the reciprocation of said rod, 5 by alternate movement thereof by said piston and laterally extending arm, said oscillatory member will be actuated to shift the valve body, and means controlling said oscillatory element for imparting a snap action to the 10 movement thereof.

3. A steam engine valve structure comprising a steam chest having an inlet, a pair of exhausts, and a pair of outlets each designed to open into an engine cylinder at one side 15 of a piston therein, a sliding valve block within the chest having a steam passageway

formed therethrough and terminating at each end in a pair of outlets, one of said pair of outlets of the valve block being designed to set up communication between an outlet of 20 the steam chest and an exhaust, a quadrant body mounted within the steam chest above said valve block, means for setting up a loose connection between the quadrant and the valve block, vertically reciprocating means in 25 the steam chest actuated by the engine piston for swinging said quadrant to shift the valve block, means for imparting a snap action to the movement of said quadrant.

In testimony whereof I affix my signature.

LOUIS E. MORRISON.
